UNITED STATES PATENT OFFICE.

EMILE BOURDELLES, OF PARIS, FRANCE, ASSIGNOR TO SCHNEIDER & CIE., OF PARIS, FRANCE, A JOINT-STOCK COMPANY.

BREECH-LOADING GUN.

1,110,105.

Specification of Letters Patent.

Patented Sept. 8, 1914.

Application filed March 20, 1914. Serial No. 826,057.

To all whom it may concern:

Be it known that I, EMILE BOURDELLES, a citizen of the Republic of France, resident of 39 rue Galilee, Paris, France, have invented new and useful Improvements in or Relating to Breech-Loading Guns, which is fully set forth in the following specification.

The present invention has for its object 10 a practical embodiment of the breech loading gun of adjustable caliber described in the specification of Patent No. 1,092,763, dated April 7, 1914. The gun described in the said specification is characterized by the fact 15 that a barrel of medium caliber and a barrel of small caliber are combined in such a manner as to furnish an additional recoiling mass during firing. In the construction described in the said specification the small 20 barrel which always remains connected with the barrel of medium caliber is fitted into the latter when the said small barrel is desired to be used while it is replaced in a support integral with the barrel of medium 25 caliber when the latter is desired to be used. In this manner although one and the same breech block is used for both barrels, it is necessary to effect a somewhat lengthy operation and to provide inside the barrel of 30 medium caliber screw threads or other fitting and fixing devices for the barrel of small caliber. According to the present invention I avoid this disadvantage by arranging the single breech block so that it is dis- 35 placeable in two housings or guides formed in line with each other in the two barrels in such a manner that according to the position imparted to it by means of suitable operating mechanism, the said block serves 40 to close the breech of the particular barrel that it is desired to employ. In order that the said invention may be clearly understood and readily carried into effect I will 45 describe the same more fully with reference to the accompanying drawings in which:

Figure 1 is a general longitudinal section of the two combined barrels, the movable breech block common to them both being represented in the position for closing the breech 50 of the barrel of medium caliber. Fig. 2 is a similar partial section showing the breech block in the position in which it closes the breech of the barrel of small caliber. Figs. 3 and 4 are rear elevations of Figs. 1 and 52 respectively.

In these figures, *a* designates the howitzer or gun of medium caliber which comprises fixing means such as the two hoops *c*, *d*, for the barrel of small caliber *b*. A housing *e* is provided in the barrel *a* for a breech block *e* which can either be held in this housing or shifted into a housing *e*² or guide formed behind the rear face of the barrel *b*. In the example illustrated the barrel *a* is integral with a hoop *f* whose central hole is 60 of a diameter corresponding to the caliber of the projectile and in a guide in this hoop a wedge *f*' can be placed and fixed to limit the travel of the movable block *e*.

In the example illustrated, the displacement of the block is obtained by the following simple means: The block *e* carries a rack *g* with which a pinion *h* is constantly in mesh; this pinion is keyed on a shaft *i* journaled in the breech end of the gun and carrying externally an operating handle *j*. The housing in the barrel *a* has a shoulder for limiting the downward travel of the block *e*. The two combined barrels might of course be arranged in juxtaposition instead of super- 75 position and similarly in the latter case the relative positions might be the reverse of those represented in the drawing.

What I claim and desire to secure by Letters Patent of the United States is:—

1. In combination, a double barrel breech loading gun, a rectilinearly movable breech block adapted to close the breech of either barrel, and means for moving said block into closing position for either barrel.

2. In combination, a double barrel breech loading gun, breech block housings formed in the walls of said barrels and in line with each other, a breech block movable in said housings adapted to close either breech, and means for moving said block into closing position for either barrel.

3. In combination, two gun barrels, one of which is provided with means for receiving the second barrel and retaining the same in parallel relation to itself, breech block housings in the walls of said barrels arranged in line with each other, a breech block movable in said housings, and means for moving the breech block into closing position for either barrel.

4. In combination, two gun barrels, one of which is provided with means for receiving the second barrel and retaining the same in parallel relation to itself, breech block

housings in the walls of said barrels arranged in line with each other, a breech block movable in said housings, means for moving the breech block into closing position for either barrel, and stops limiting the movement of said block in both directions of movement.

In testimony whereof I have signed this

specification in the presence of two subscribing witnesses.

EMILE BOURDELLES.
